(57) **CLAIM**

The ornamental design for a desk, as shown and described.

DESCRIPTION

FIG. 1 is a perspective view of a desk.

FIG. 2 is a front elevation view thereof. A rear elevation view is identical to the front elevation view.

FIG. 3 is a right side elevation view thereof. A left side elevation view is identical to the right side elevation view.

FIG. 4 is a top plan view thereof.

FIG. 5 is a bottom plan view thereof.

FIG. 6 is a cross-sectional view taken along the line 6-6 in FIG. 2.

FIG. 7 is a cross-sectional view taken along the line 7-7 in FIG. 3; and,

FIG. 8 is a cross-sectional view taken along the line 8-8 in FIG. 3, which omits the internal structure.

The broken lines shown in the drawings illustrate portions of the desk that form no part of the claimed design.

1 Claim, 8 Drawing Sheets
